UNITED STATES PATENT OFFICE.

BERT W. KING, OF DETROIT, MICHIGAN.

DESIGN FOR A COMPUTING-SCALE.

57,840.

Specification for Design.

Patented May 10, 1921.

Application filed October 4, 1920. Serial No. 414,677. Term of patent 14 years.

To all whom it may concern:

Be it known that I, BERT W. KING, a citizen of the United States, residing at Detroit, in the county of Wayne and State of Michigan, have invented a new, original, and ornamental Design for a Computing-Scale, of which the following is a specification, reference being had to the accompanying drawings, forming part thereof.

Figure 1 is a perspective view of a computing scale showing my new design.

Fig. 2 is a rear elevation of the scale.

I claim:

The ornamental design for a computing scale, as shown.

BERT W. KING.
